UNITED STATES PATENT OFFICE.

JOSEPH A. HASLINGER, OF OLDSMAR, FLORIDA.

ADVERTISING SIGN.

Application filed February 21, 1925. Serial No. 10,877.

This invention relates to advertising signs, and has for one of its objects the provision of a novel, simple and durable device of this character which shall be especially adapted for advertising gasoline and automobile tires, tubes and other accessories.

A further object of the invention is the provision of a device of the character stated which shall be especially adapted to contain a device for indicating the price of an advertised product and which may be readily changed from time to time as the price of the product increases or decreases.

A still further object of the invention is the provision of a device of the character stated which will withstand the weather and rough usage, which can be shipped knocked down, and which may be readily erected by an unskilled person.

With the above and other objects in view, the invention consists of the construction, combination and arrangement of parts hereinafter fully described and claimed, and illustrated in the accompanying drawings,

25 wherein:—

Figure 1 is an elevational view of an advertising sign constructed in accordance with my invention;

Figure 2 is a view in edge elevation of the sign;

Figure 3 is a top plan view of the sign;

Figure 4 is a sectional view taken on the vertical plane indicated by the line 4—4 of Figure 2;

35 Figure 5 is a sectional view taken on the vertical plane indicated by the line 5—5 of Figure 1, and

Figure 6 is a sectional view taken on the horizontal plane indicated by the line 6—6 of Figure 1.

Corresponding and like parts are referred to in the following description, and designated in the several views of the drawings, by similar reference characters.

45 The advertising sign includes a vertical frame which comprises a bottom 1, sides 2 and a top 3. The frame is reinforced by triangular braces 4 and 5 secured in the corners thereof, brace bars 6 positioned between the lower braces 4 and secured thereto and the bottom 1, and brace bars 7 positioned between the top braces 5 and secured thereto and the top 3. A bench board 8 arranged within the frame adjacent the bottom 1, is secured at its ends to the sides 2 and is supported at its center by an up-

right piece 9 which is positioned between and secured the bottom 1 and bench board 8. The braces 4, 5, 6 and 7 and the bench board 8 are strengthened and reinforced by cleats 10. The frame is mounted upon a base which comprises end supporting members 11 which project for a considerable distance beyond the opposite sides of the frame, and spacing and bracing members 12 which are positioned between and secured to the members 11.

All the parts thus far described are made of wood. The bench board 8 is adapted to support the numeral or price changing device forming the subject matter of my co-pending application, filed February 21st, 1925, Serial Number 10,878, and illustrated by dotted lines in Figure 4. As shown the numeral or price changing device comprises a hollow base 13 mounted upon and secured to the bench board 8, a hollow head 14 supported from the base 13 by a board 15, and reinforcing straps 16 secured to the head 14 and to the ends of the base 13. 80 Bolts 17 are carried by the head 14 and pivotally mounted thereon are rods 18 to which are secured numeral bearing plates 19. A pull cord 20 is secured to each of the plates 19 and passed through key hole slots, not shown, in the ends of the base 13. The cords 20 are provided with knots or stops 21 which when in contact with the outer sides of the ends of the base 13 about the noncircular portions of the key hole 85 slots maintain the plates 19 in an outwardly inclined or non-exhibiting position and which when moved into registration with the circular portions of the key hole slots permit the plates to gravitate to a vertical 90 or exhibiting position. The cords are also provided with pull buttons 22 each of which bears a numeral corresponding to the one on the plate with which it is connected. To permit the pull buttons to be arranged outwardly beyond the sides 2 of the frame so that they may be conveniently reached, said sides are provided with horizontal openings 23 through which the pull cords pass. To protect the pull cords 20 and to prevent unauthorized persons from gaining access thereto, covers 24 are hinged as at 25 to the outer surfaces of the sides 2 and are adapted to be secured in closed position by locks 26.

100 The open sides of the frame are closed by circular plates 27. These plates are made

of metal and are provided with openings 28 through which may be seen the plates 19 that are in exhibiting position. The openings are closed by transparent panels 29 which are secured within a frame 30 preferably formed integrally with the plates 27. Any advertising matter may be placed upon the braces 4, the plates 27 and a board 31 secured to the top 3 of the frame. A housing 32 is secured to the upper edge of the board 31 and the upper ends of supports 33 extending upwardly from and secured to the sides 2 of the frame. The housing 32 extends beyond the opposite sides of the sign and carries electric lamps 34 for illuminating the sign at night. The housing 32 is preferably made of metal and the board 31 and supports 33 of wood.

From the foregoing description, taken in connection with the accompanying drawings, the advantages of the construction of the sign will be readily apparent to those skilled in the art to which it appertains. While I have described and illustrated what I now consider to be the best embodiment of the sign, I desire to have it understood that such changes may be made therein as are within the scope of the invention as claimed.

What is claimed is:—

1. An advertising sign comprising a

frame, means for strengthening and reinforcing the frame, a bench board within the frame for supporting a price indicator having pivoted numeral bearing plates and pull cords connected to the plates, the sides of the frame being provided with horizontal openings for the passage of the pull cords, plates secured to the frame and provided with openings through which the numeral bearing plates may be seen, and covers for the openings and pull cords and secured to the sides of the frame.

2. An advertising sign comprising a frame of open rectangular formation, triangular braces secured in the corners of the frame, brace bars secured to the triangular braces and top and bottom of the frame, a bench board positioned within the frame adjacent the bottom thereof and adapted to support a price indicator, an upright piece positioned between the bottom of the frame and bench board and adapted to support the latter at its center, and plates secured to the open sides of the frame and extending over a portion only of the triangular braces, said plates being provided with openings through which the prices indicated may be seen.

In testimony whereof I affix my signature.

JOSEPH A. HASLINGER.
